BLASTING DEVICE

James Taylor, Saltcoats, Scotland, assignor to Imperial Chemical Industries Limited, a corporation of Great Britain

Application October 27, 1937, Serial No. 171,391
In Great Britain October 29, 1936

5 Claims. (Cl. 102—10)

This invention relates to blasting devices, particularly to those of the kind comprising a pressure-resistance reutilisable container, a charge of a solid material capable of undergoing a non-detonating gas-evolving decomposition when locally initiated, and means for locally initiating the decomposition of the said charge.

Blasting devices of this kind have been proposed in which the container is charged at atmospheric pressure with a solid material of the kind described, and is fitted with a valve or rupturable disc seal of high tensile strength material adapted to release the products of decomposition of the charge when the internal pressure has attained a predetermined and considerable value sufficient to produce a blasting effect when the device has been suitably located in a borehole.

Blasting devices of this latter kind have been used, in which the charges of solid material comprise mixtures of ammonium chloride and sodium nitrite. A characteristic feature of these compositions is that their rates of exothermic decomposition, and hence their rates of development of gas pressure when confined, do not become great enough to produce a blasting effect until the decomposition is taking place under an already considerable pressure. This property is desirable in that the unconfined compositions may be handled with safety; but hitherto they have not been considered suitable for use as blasting explosives, except when in proper association with a pressure-resistant venting container, since if they are loosely tamped in a borehole, or if the borehole has breaks or fissures, any gas pressure developed by their initial decomposition will leak away too rapidly for the complete decomposition of the charge to produce an effective blast.

In the devices used hitherto, in which the charged container is adapted to vent when the internal pressure reaches a value suitable for blasting, the considerable pressure mentioned above is built up by the gas evolved during the relatively slow decomposition of the charge immediately after its initiation at substantially normal pressure. In such devices the whole of the container, and also the material of the seal or venting portion, is designed to withstand for a prolonged time static pressures up to the venting pressure. The provision of a release valve or rupturable disc seal necessitates the use of a container of special and complicated construction and the provision of screwed unions and a detachable venting cap. The elimination of such features is to be desired, not only from the point

of view of economy and simplicity, but also with a view to a more efficient use of the energy of discharge of the gases and the elimination of deterioration of the apparatus due to erosion at the venting end of the device.

This invention has as an object to provide a blasting device which does not require any screwed unions or detachable venting cap. A further object is to provide a blasting device which shall be more simple and economical than known blasting devices. Further objects will appear hereinafter.

These objects are accomplished by the following invention. I have found that blasting devices of the kind venting at a predetermined and considerable pressure may be constructed, without any necessity for the provision of a seal of which the material is capable of prolonged resistance to pressures less than the venting pressure, by making use of the pressure-resisting properties of a column of granular or like material supported in a rigid tube, if adequate support is given to the column of granular material within a pressure-resistant tube, preferably by a gas-tight supporting and sealing member. The support need only withstand a static pressure that is small relative to the pressure at which the container is intended to vent, although it must be capable of withstanding pressure substantially greater than atmospheric. Thus for example the support alone must be capable of withstanding an internal pressure of the order of 40 atmospheres but need not withstand pressures greater than about 1 ton per square inch. When such support is used in conjunction with a column of sand that is short relative to the length of sand tamping hitherto employed with safety explosives to ensure a safe blast in a dangerous atmosphere, the assembly can withstand pressures exceeding 30 tons per square inch.

Referring generally to the drawing there is depicted therein a view in vertical cross-section of a blasting device according to the present invention.

In greater detail the cylindrical steel tube 1 is depicted as closed at one end. Adjacent to said closed end is a charge 2 of sodium nitrite and ammonium chloride. Embedded in said charge is an electric igniter 3, the leads 4 of which pass downward and out through the other end of said steel tube. Below the aforesaid charge 2 is a column of sand 5 supported by a plaster of Paris plug 7 retained in place by means

of a circular groove 6 in the inner wall of said tube.

The resistance offered to a static pressure by an adequately supported column of a granular material is shown by the following experimental results. In the experiments, a steel tube, 1 1/4" inside diameter, was packed with various lengths of sand supported on a plug of plaster of Paris, 2" long, cast into place. The static pressure required in each case to dislodge the assembly from the tube is given in the following table. The pressure required to dislodge the plaster of Paris plug alone was approximately 1/2 ton per square inch.

Height of sand column	Breakdown pressure
Inches	Tons per square inch
1	0.53
2	0.87
3	4.07
3 1/2	11.7
4	14.5

The usual venting pressure of a 1 1/4" internal diameter blasting device of the kind described is 12 tons per square inch.

According to the present invention, a blasting device comprises a pressure-resistant reutilisable container provided with a seal adapted to yield under an internal pressure substantially higher than atmospheric pressure, but considerably less than the pressure at which the device is intended to vent; a charge of a solid material capable of undergoing a non-detonating gas-producing exothermic decomposition after being locally initiated; means for local initiation of the charge; and a quantity of a granular or like substance having the property of packing under pressure, completely filling the free space between the charge and the seal, and in amount such that the device vents at a pressure sufficient to exert a blasting effect, but insufficient to cause any deformation or other damage to the container. The actual magnitude of the venting pressure will be a function of the length of the column of sand or like granular material; and it will be understood that this length must be predetermined accordingly.

For example, the following table indicates the conditions under which a series of successful blasts have been carried out. In each case the charge used was a finely-powdered mixture of sodium nitrate and ammonium chloride stabilised with 1.5% light magnesium oxide. The tubes were 1 1/4" inside diameter, and were sealed at the open end with a 2" plaster of Paris plug. The space between the charge and the seal was filled with sand. The igniter used was constructed according to specification Serial No. 758,317, filed January 19, 1934.

Weight of charge	Length of tube	Length of sand	Maximum pressure
Grams	Inches	Inches	Tons per square inch
150	17	5 1/2-8	12
	30	12-15	15
200	15	2-4	8 1/2
	20	6-8 1/2	12
250	25	12-14	15
	22	7-9	15
	28	10-15	20

The following examples illustrate but do not limit the invention.

Example 1

5 A cylindrical high-tensile steel tube, 1 1/4 inches internal diameter, 1 3/4 inches external diameter, 20 inches long and closed at one end, is charged with 200 gm. of a mixture of sodium nitrite and ammonium chloride, granulated 24-100 mesh, containing 1.5% light magnesium oxide as stabiliser. A suitable igniter, such as a 30-grain powder fuze or a safety igniter, is embedded in the charge, and the leads are brought forward through the open end of the tube. The charge occupies approximately 11 inches of the tube. The remainder of the tube up to 2 inches from the mouth is filled with sand, well shaken down but not rammed hard. A plug of plaster of Paris is then cast into the remaining two-inch space at the open end of the tube, which is provided with grooves or holes to assist in keying the plaster of Paris plug to the tube. When initiated in the usual manner, the charge vents at an internal pressure of approximately 9 tons per square inch; and when the device is well tamped in a bore-hole, a satisfactory blasting effect is obtainable.

Example 2

A tube of the kind described in Example 1, 26 inches long, is charged with 250 gms. of a mixture as used in Example 1, which is tamped into the tube. Subsequently 8 inches of dry sand are introduced and are covered by a 2 inch plaster of Paris plug. The means of initiation is a 30 grain powder fuze located at the base of the tube. 30 When initiated, the charge vents at a pressure of 10 tons per square inch and produces a satisfactory blast.

Example 3

A tube 29 inches long is charged with 300 gms. of a mixture as in Example 1. The tamping consists of 12 inches of dry sand and a 2 inch plaster of Paris plug. The means of initiation is a safety igniter of the type described in copending application Serial No. 758,317, filed January 19, 1934, situated at the base of the tube. When initiated, the charge vents at a pressure of 16 tons per square inch.

40 A type of pressure-resistant container suitable for use according to the invention is a plain cylindrical steel tube closed at one end and if desired otherwise free from constructions, screwed fittings, or any other device likely to prevent free egress of the contents of the tube. Tubes open at both ends, and having the charge placed more or less evenly between two columns of granular packing material and two sealing plugs, may also be used: but the single-open-end tube is preferred.

45 Another suitable type of container is a cylindrical steel tube hemispherically closed at both ends and provided with lateral venting apertures near one end. In a device of this kind the blast does not produce such a reaction tending to cause the tube to be moved in an axial direction as may happen when a simple open-ended tube is used.

50 As charges I may use the gas-producing compositions described and claimed in U. S. Patents 2,038,772, 712,052, 2,048,827, copending applications Serial Nos. 68,143 and 96,121, filed March 10, 1936, and August 14, 1936, respectively, and in co-pending application Serial No. 162,221, filed September 2, 1937; or any other suitable composition having the properties described. The invention is best applied however, when used with

charges that do not produce a blasting effect, when used under comparable borehole conditions, except when contained in a pressure-resistant enclosure adapted to confine the products of their decomposition during its initial stages.

As means of initiating the charges I may use electrically-fired powder fuzes or detonators, or safety igniters.

The packing material used is preferably sand, or a similar material, the essential property being that it must "pack" under the application of rapidly increasing pressure; chalk or china clay may also be used. Crystalline salts or their mixtures may also be used, and in some cases may have particular advantages, such as a capability of absorbing noxious fumes. The gas-producing material itself or its ash may constitute, wholly or in part, the packing material.

As a sealing material I may conveniently use a plug of plaster of Paris, cast into place; but an oversize wooden or like plug driven into the mouth of the tube will also serve, although its resistance is more difficult to gauge. When using seals cast into place, I prefer to use sealing materials that expand on solidification, of which plaster of Paris is the most convenient. The seal may be, if desired, formed after the device has been loaded in the borehole, for example by soaking the granular tamping at the mouth of the tube with water and tamping the borehole next to the tube with solid carbon dioxide so that a plug of ice is formed.

This invention is useful in the art as it provides new and effective blasting devices which are easy and economical to make.

Certain blasting devices constructed according to the invention are safe for use in fiery and gassy mines, and may even be assembled with safety at the working face.

For example, devices of the foregoing type may be loaded with the charges described and claimed in U. S. Patent No. 2,038,772 and copending application Serial No. 96,121, filed August 14, 1936, and provided with an initiating device of the type described in co-pending application Serial No. 758,772.

As many apparently widely different embodiments of this invention may be made without departing from the spirit and scope thereof it is to be understood that I do not limit myself to the specific embodiments thereof except as defined in the appended claims.

I claim:

1. A non-detonating gas-generating blasting

device comprising a non-destructible re-usable pressure-resistant container, a charge of non-detonating gas-producing material disposed in said container, igniting means disposed adjacent to said charge, venting means confining said charge in said container comprising a column of inert granular material and a supporting member located in the end of said container adjacent to said inert granular material.

2. A non-detonating gas-generating blasting device comprising a non-destructible re-usable pressure-resistant container, a charge of non-detonating gas-producing material disposed in said container, igniting means disposed adjacent to said charge, venting means confining said charge in said container comprising a column of inert granular material and a cast plug of material having the property of expansion on solidification disposed in the end of said container and supporting said column of inert granular material.

3. A non-detonating gas-generating blasting device comprising a non-destructible re-usable pressure-resistant container, a charge of non-detonating gas-producing material disposed in said container, igniting means disposed adjacent to said charge, venting means confining said charge in said container comprising a column of inert granular material and a plug of plaster of Paris cast into place in the venting end of said container supporting said column of inert granular material.

4. A non-detonating gas-generating blasting device comprising a non-destructible re-usable pressure-resistant container, a charge of non-detonating gas-producing material disposed in said container, igniting means disposed adjacent to said charge, venting means confining said charge in said container comprising a column of sand and a plug member disposed in the end of said container supporting said sand.

5. A non-detonating gas-generating blasting device comprising a re-usable pressure-resistant container consisting of a cylindrical steel tube closed at one end, a charge of non-detonating gas-producing material disposed within said tube adjacent to the closed end thereof, an igniter embodied in said charge, a column of sand disposed in said tube between the locus of said charge and the opened end of said tube, keying means in the mouth of said tube, and a plug of plaster of Paris cast into place closing said mouth and co-operating with said keying means.

JAMES TAYLOR.
